UNITED STATES PATENT OFFICE.

AUGUST L. N. FLEMING, OF LYNDHURST, NEW JERSEY, AND WILLIAM T. CRISWELL,
OF NEW YORK, N. Y.

SAFETY DEVICE.

Application filed December 30, 1922. Serial No. 609,995.

To all whom it may concern:

Be it known that we, AUGUST L. N. FLEMING and WILLIAM T. CRISWELL, a citizen of the Republic of France and a citizen of the 5 United States, respectively, and residents of Lyndhurst, in the county of Bergen and State of New Jersey, and of New York, in the county of New York and State of New York, respectively, have invented certain 10 new and useful Improvements in a Safety Device, of which the following is a full, clear, and exact specification.

This invention relates to a class of devices adapted to be used for sounding an alarm 15 in emergency.

Our invention has for its object primarily to provide a safety device designed to be employed on movable bodies, such as automobiles, autotucks, motorcycles, motor-boats and other vehicles or elsewhere for sounding an alarm to give timely warning in event of mistaken or surreptitious appropriation of the vehicle for use, or improper 20 operation of the body, and which is of a form adapted to be operated by the vehicle or body without interfering with or obstructing the ordinary operation of the vehicle or body as well as being of a form 25 adapted to operate to cause the alarm to sound should the device be detached or broken from its mounting with the vehicle or body.

The invention resides mainly in the provision of an alarm with mechanism for sounding the alarm. The mechanism is adapted 30 to be controlled or adjusted or releasably locked against normally causing the alarm to sound when in operation and when readjusted or unlocked the mechanism is adapted 35 to be operated for sounding the alarm in emergency so that the employment of the device on a movable body or vehicle will serve to afford protection when the vehicle is parked or garaged from being stolen or 40 wrongly selected or when the body is operated by an unauthorized person.

Other objects of the invention are to provide controlling means which is operative according to a determined adjustment for 45 locking and unlocking or adjusting and readjusting the alarm sounding mechanism; to provide spring actuating means for independently operating the mechanism with its separation from the vehicle or body; and 50 to provide a safety device which may be

made in any appropriate shape and size, and which combines simplicity of construction, efficiency and durability.

With these and other objects in view, the invention will be hereinafter more fully described with reference to the accompanying drawings forming a part of this specification in which similar characters of reference indicate corresponding parts in all the views, and will then be pointed out in the 60 claims at the end of the description.

In the drawings, Figure 1 is a sectional view, partly in detail and partly fragmentary, taken through one form of safety device embodying our invention as applied for 65 operation by a drive member of a vehicle.

Fig. 2 is an enlarged elevation, partly broken away and partly in section, of the 70 spring actuating means for independently operating the alarm sounding mechanism.

Fig. 3 is an enlarged sectional view, partly 75 in detail and partly fragmentary taken through the spring actuating means shown in Fig. 2.

Fig. 4 is an enlarged elevation, partly 80 broken away and partly in section, of the controlling means used in the device for locking and unlocking the alarm sounding mechanism, and

Fig. 5 is an enlarged sectional view, partly 85 in detail and partly broken away, taken on the line 5—5 of Fig. 4.

The device has a casing 10 which may be of suitable material in any appropriate size and shape, though the form of the casing 90 illustrated, has a cylindrical wall 11 with a partially spherical or cup-shaped front end, as 12, and a partially spherical or cup-shaped rear end, as 13. The casing may be divided into two sections 14, 15 which 95 are detachably connected by part of the inner face of the wall of the section 15 being interiorly threaded, as at 16, and in these threads are screwed the exterior threads, as 17, of the section 14. In spaced 100 parts of the wall of the section 14 may be openings, as 18, 19 and in the wall of the section 15 may be an opening, as 20. The openings 18, 19, 20 serve as sound vents, and by providing the openings 18, 19, one in the 105 lower part and one in the upper part of the wall of the section 14 the openings also serve to prevent liquid or sand or other foreign material when surreptitiously passed therethrough from remaining in the interior 110

of the casing. Also on the exterior of the wall of the section 15 of the casing may be provided baffles or flanges, as 21, 22, 23, which are spaced from the wall of the casing 5 as well as being of sizes for obstructing direct access through the openings or sound vents 18, 19, 20. On the lower part of the wall of the section 15 may be a downwardly protruding bearing 24 of a suitable length with 10 its bore leading into the interior of the casing, and on the lower end of the bearing may be a flange 25 to allow the casing to be bolted, as at 26, or otherwise fastened to a suitable support, as 27. Centrally of the end 15 wall 12 of the section 14 of the casing is a bearing 28 having an exteriorly threaded end extending into the casing, and projecting into the section 15 from the central part of its end wall is a bearing or boss, as 29. 20 Within the casing at the inner end of its section 14 is a stationary vertical wall or bracket 30 arranged so that both of its ends terminate in spaced relation to the wall of this section. In the section 15 of the casing 25 in spaced proximity, to the boss 29 is a fixed partition 31 extending crosswise of the interior of the casing, and the center of this partition is cut-out to provide a large opening, as 32. Fastened, at 33, to the partition 30 30 may be a plate 34 having in its central part an opening 35 in register with the opening 32 of the partition as well as being in register with the bore or socket of the boss 29.

35 Within the casing is a sound producing device or alarm, as 36, which may be of any appropriate type adapted when operated to give a timely warning in emergency, though the alarm shown is in the form of a bell disposed within the section 14 of the casing. 40 The bell is preferably of a shape approximately similar to the shape of the casing 14, while being of a size so that its wall is in closely spaced proximity to the wall and curved end of the section. In the arched end of the bell is an opening through which the bearing 28 of the section 14 is disposed, and the bell may be removably fastened by suitable means, such as a nut 37 screwed on the 45 bearing for clamping the bell between the nut and the curved end of the section. We prefer to employ a class of bell or alarm adapted to produce a distinctive noise or ring so that when rung its sound waves will 50 pass through vents 18, 19, 20 of the casing for attracting the attention of nearby persons.

Within the casing 10 is provided mechanism, as 38, which is operative for sounding 60 the alarm or bell 36. This mechanism is adapted to be controlled or adjusted or releasably locked against normally sounding the alarm during its operation, and when unlocked the mechanism is adapted to be operated for sounding the alarm in emer-

gency. The mechanism 38 may be of any suitable construction, though the mechanism illustrated includes main operative parts, as 39, also parts, as 40, which are operative for serving as means to sound the alarm, and means or parts, as 41, adapted to be adjusted according to a given adjustment whereby the alarm sounding means 40 will be connected to and disconnected from the main parts 39 of the mechanism for being operated to prevent the alarm from sounding with the operation of the mechanism and to cause the alarm to sound a warning at periods when the mechanism is operated. The main parts 39 of the mechanism may be 80 operated by driven means, as 42, which is detachable from the mechanism, and spring actuated means, as 43, is provided for operating the mechanism independently when the driving means 42 is separated from the 85 mechanism.

The main operative parts 39 of the mechanism 38 has a driven member or sleeve member 44 of a clutch 45 having a second sleeve 46, and the opposed ends of these sleeve members terminate with interfitting ratchet teeth, as 47. The sleeve member 44 of this clutch is freely revolvable on a shaft 48 having one of its ends journaled in a bore in the stationary bracket 30 of the casing 10, and the shaft extends through the opening 35 of the plate 34 and through the opening 32 of the partition 31 of the casing as well as having its second end journaled in the bearing 29 of the section 15 of the casing. The shaft 48 is of a length so that its second end is spaced from the bottom of the bore of the bearing 29 to allow the shaft to be slidably moved as well as being rotated, and the sleeve member 46 is fastened, at 49, to the shaft for causing the member 46 to revolve with the rotation of the shaft. The shaft 48 is normally held yieldingly outward of the bearing 29 by a spring 50 which encircles the shaft with its ends abutting against the bearing 29 and the sleeve member 46 of the clutch 45. This spring also serves to normally retain the teeth 47 of the sleeve members of the clutch 45 in releasable engagement. Integral with the end of the sleeve member 44 opposite to the teeth 47 is a bevel gear 51 which is freely revolvable on the shaft 48, and also on the sleeve member 44 of the clutch is held a gear 52 so that when the bevel gear 51 is 110 rotated from left to right the gear 52, members of the clutch 45 and the shaft 48 will be driven in unison. When the bevel gear 51 is reversely revolved the ratchet teeth 47 of the members of the clutch 45 will allow 125 the bevel gear 51 with the gear 52 and the sleeve member 44 to be simultaneously revolved independent of the shaft 48, as will be hereinafter more fully explained.

The parts 40 which serve as means for 130

sounding the alarm in emergency is composed of a well known form of hammer, as 53, having a spring rod 54 with a head, as 55, on one of its ends. The other end of 5 the rod 54 is held to a sleeve, as 56, of a lever 57 so that the head of the hammer is normally in contact with the bell or alarm 36. The sleeve 56 is rotatable on a stud 58 extending from an arm, as 59, projecting 10 angularly from the upper end of the bracket 30, and at the juncture of this arm 59 with the bracket 30 is a bearing 60, while in the lower wall of the bore of this bearing is a crosswise keyway or slot, as 61. The lever 15 57 has a trip or curved finger 62 depending from the sleeve 56, and extending from the sleeve in an opposite direction to the rod 54 of the hammer is an arm 63 which terminates in spaced relation to the plate 34 of the 20 partition 31. To the free end of the arm 63 is held the upper end of a spring, as 64, having its other end held to the plate 34 below the arm 63. The spring 64 is tensioned for normally forcing the arm 63 in 25 a downward direction so that the lever 57 will be swung for yieldingly holding the head of the hammer 53 in contact with the ball or alarm 36 as well as yieldingly holding the trip or finger 62 in a direction so 30 that when the finger is moved back and forth the lever 57 will rotatably move on stud 58 for causing the hammer to ring the bell to sound an alarm. The downward movement of the arm 63 is limited by a 35 stop or pin 65 which protrudes from the wall of the casing 10. These parts 40 are adapted to be disconnected from the main parts 39 of the mechanism 38 for preventing sounding of the alarm at desired intervals 40 during the operation of the mechanism, and these parts 40 are adapted to be also operatively connected to the mechanism by the adjustable parts 41 which serve as means whereby the parts 40 will be operated to 45 sound the alarm with the operation of the mechanism.

The adjustable parts 41 include a shaft 66 having one of its end portions slidably disposed through the bearing 60 of the 50 bracket 30, and protruding from this shaft is a key or pin 67 which is slidably disposed in the keyway 61 of the bearing for guiding the movement of the shaft as well as preventing the shaft from tending to 55 revolve in the bearing. One end of the shaft extends beyond the bracket 30 toward the curved end wall of the section 14 of the casing. Approximately one-half of the shaft 66 including its second end portion is reduced in diameter to provide an annular 60 shoulder 68, and the second end of the shaft is rotatably and slidably disposed through a bore, as 69, provided in the upper part of the plate 34 of the partition 31 of 65 the casing. On the forward end of the shaft 66 is a head, as 70, having a laterally and forwardly protruding locking lug or bolt or tooth 71 which is preferably of a form having a vertical right angled free end or edge spaced from the head. Encircling 70 the shaft between the head 70 and the bearing 60 of the bracket 30 is a spiral spring 72 which is tensioned for normally serving to force the shaft 66 with the head 70 and locking lug 71 in a direction from the 75 bracket 30 toward the curved end wall of the section 14 of the casing. On the reduced portion of the shaft is a sleeve 73 having on one of its ends a cam or collar 74 with a curved lug, as 75, protruding from one 80 of its edges so that the lug overlaps the sleeve in opposition to finger 62 of the lever 57. The cam or collar 74 is fastened, at 76, to the sleeve 73, and on the other end of the sleeve is held a pinion 77 which is in mesh 85 with the gear 52 of the main part 39 of the mechanism. The sleeve 73, cam collar 74 and pinion 77 are freely revolvable on the reduced portion of the shaft 66 with one end of the sleeve rotatably abutting against 90 the shoulder 68 of the shaft, while the other end of the sleeve rotatably abuts against a collar, as 78, which is fastened on the shaft to prevent the sleeve, cam collar and pinion from accidentally shifting on the shaft. 95 The sleeve, cam collar and pinion are thereby movable back and forth with the slidable adjustment of the shaft 66, and these parts may be rotated independently on the shaft. The sleeve 73, cam collar 74 and pinion 77 100 are also arranged relative to the lever 57 of the parts 40 of the mechanism so that with the slidable adjustment of the shaft 66 the lug 75 of the collar 74 will move into and out of contact with the finger 62 of the lever 57 for disconnecting the parts 40 to prevent their operation for sounding the alarm, and to connect the parts 40 for sounding the alarm when the main parts 39 105 of the mechanism is operated for rotating the gear 52. The pinion 77, sleeve 73 and cam collar 74 will then be revolved on the shaft 66, and the lug 75 will at intermittent intervals engage the finger 62 of the lever 57 for causing the finger with the sleeve 56 and arm 59 to rock on the stud 58, which in turn will move the spring rod 54 so that the head 55 of the hammer will intermittently strike the bell 36 for sounding the alarm. 110

The parts or driven means 42 may be of any appropriate construction adapted to be operated by an operative member, as 79, which, as shown, may be in the form of a drive shaft of an automobile, autotuck, 115 motorboat or other vehicle, though the device may be used elsewhere, such as on a movable body which is susceptible of being wrongly appropriated. The driven parts 42 illustrated consists of a driven member or 120

vertical shaft 80 which is journaled in the bearing 24 of the casing 10, and this shaft is of a diameter whereby it will move downwardly in the bore of the bearing when unsupported. In the wall of the bearing 24 of the casing 10 centrally of the shaft 80 is an annular recess, as 81, in communication with the bore of the bearing. The upper end of the shaft 80 terminates at the upper end of the bearing 24, and protruding from the upper end of the shaft is a rightangled lug 82 which may extend entirely or partly across the center of the upper end of the shaft. The lower end of the shaft 80 protrudes below the bearing 24, and extending downwardly from the lower end of the shaft may be a lug, as 83, in contact with the shaft or drive member or operative part 79 of a vehicle or movable body for serving to hold in its normal position the shaft 80 in the bearing 24 of the casing when the device is mounted to the support 27 above the drive member. On the lower end of the shaft 80 below the bearing 24 is held a bevel gear 84 which is in mesh with a bevel gear 85 keyed on the drive member or shaft 79. On the upper end of the shaft 80 in straddle arrangement on the lug 82 of the shaft 80 is detachably disposed the lower grooved end 86 of a short shaft or stud 87 which extends interiorly of the casing toward the shaft 48 of the mechanism 38. The diameter of the stud may be smaller than the diameter of the shaft 80 and on the upper end of the stud 87 may be a pin or lug 88. On the stud 87 is a bevel gear 89 meshing with the bevel gear 51 of the mechanism 38. In the lower end of the wall of the bore of the bevel gear 89 is a rightangled groove, as 90, in which is removably seated the lug 82 of the shaft 80 so that when the drive member 79 and the bevel gear 85 are rotated the bevel gear 84, shaft 80 and stud 87 will be driven to rotate the bevel gear 89 which in turn will operate the parts 39 of the mechanism 38 by driving the bevel gear 51 of the mechanism. The stud 87 is of less diameter than the diameter of the shaft 80, and this stud is also of a size so that it is slidably movable in the bevel gear 89. In event of the device being wrongfully separated from the support 27 for disconnecting the driving means 42 from the drive member or movable body 79 by removing the bolts 26 from the flange 25 of the bearing 24, or should the device be purposely stricken from the support the bearing 24 of the casing will likely be severed. The bevel gear 89 will then be disconnected from the shaft 80 to cut-out operation of the driving means 42 for operating the parts 39 of the mechanism 38 by the shaft 80 being slidably moved downwardly in the bearing 24 to remove the lug 82 from the groove 90 of the bevel gear 89.

This separation of the shaft 80 with the bevel gear 89 is accomplished by means including a stud 91 which is journaled in an arm or lug 92 provided on the lower part of the fixed bracket 30 of the mechanism. On the stud 91 is held a sleeve 93 from which extends an arm or presser member 94 having its free end part bearing upon the lug 88 of the shaft 87 of the bevel 89. Extending upwardly from the sleeve 93 is a short bar or plate 95 disposed on an oblique angle relative to the presser member 94, and on a pin at the upper end of the plate 95 is a roller, as 96, which is revolvably seated between two spaced collars 97, 98 held on the shaft 48 of the mechanism. On the stud 91 in spaced relation to the roller plate 95 is a bar 99 which protrudes upwardly in spaced relation to the bracket 30, and pressing against the upper end of the bar 99 is one end of a spiral spring 100 having its other end seated in a socket in the upper part of the bracket 30. The spring 100 may be of slightly less tension than the spring 50 for normally serving to force the bar 99 in a direction from the bracket 30 so that with the separation of the casing 10 from the drive member 79 the tension of the spring 100 will force the bar or lever 99 from the bracket 30. The stud 91 and sleeve 93 will then be rotatably moved to cause the plate 95 and roller 96 to swing in a direction from the fixed bracket 30, and the collars 97, 98 will be shifted for slidably moving the shaft 48 in a direction toward the bottom of the boss 29 of the section 15 of the casing 10. With the movement of the collars 97, 98 and the plate 95 the sleeve 93 will revolve on the stud 90 for forcing the presser member 94 downwardly. With the separation of the casing 10 from the support 27 the downward movement of the presser member will cause the stud 87 to slidably move downward in the bevel gear 89, and the shaft 80 will also be slidably moved downwardly by the stud in the bearing 24 of the casing for removing the lug 82 from the groove 90 of the bevel 89. The driving means 42 will thereby be separated from the part 39 of the mechanism 38. When the shaft 80 is forced downwardly in the bearing 24 of the casing it will be prevented from being reversely moved upwardly in the bearing by a pawl 101 which is movably arranged in a recess, as 102, provided in the central part of the shaft, and the lower end of the pawl is rotatably mounted on a pin 103 provided on the shaft crosswise of the interior of the recess so that the engaging free upper end of the pawl movably rests against the wall of the bore of the bearing a slight distance above the annular groove 81 of the bearing. In a socket, as 104, provided in the shaft 80 so that it leads into the recess 102 is a

spiral spring 105 which presses against the free end part of the pawl 101 for serving to normally force the movement of the pawl outwardly of the recess 102. When the 5 shaft 80 is moved sufficient distance downwardly in the bearing 24 the pawl will be yieldingly forced by the tension of the spring 105 out of the recess 102 so that the free end of the pawl will extend into the flange 111 so that the collar movably contacts with the face of the plate 34 opposite to the housing. One end of the spring 106 is held, at 117, to the sleeve member 44 of the clutch 45 within the housing 107 so 70 that the convolutions of the spring surround the clutch, and the other end of the spring is held to a pin 118 which extends from the side wall 109 across the interior of the housing to and through a hole in the side wall 108 of the housing so that the second end of the pin protrudes beyond the side wall 108. In the side wall 108 of the housing in spaced proximity to the pin 118 is an elongated curved slot or opening, as 119, which 75 extends crosswise of the spring 106 from the annular wall or rim 110 of the housing toward the sleeve member 44 of the clutch 45. In part of the outer edge of the side wall 108 and in an adjacent part of the 80 rim 110 of the housing in proximity to the pin 118 is a socket, as 120, of substantially a wedge shape and in part of the outer edge of the side wall 109 as well as in an adjacent part of the rim 110 of the housing is 85 another substantially wedge shaped socket, as 121, which is preferably positioned in spaced relation to the socket 120. As shown in Fig. 4, the sockets 120 and 121 are oppositely disposed for removably receiving 90 pawls, as 122 and 123. The pawl 122 is in the form of a curved tapered short bar having one of its ends rotatably mounted on a pin 124 extending from a lug 125 which 95 protrudes interiorly of the casing from the lower part of the wall of the section 15 of the casing under the housing 107. Lengthwise of the pawl 122 is a socket 125 which leads into the aperture of its pivoted end, and in this socket is a spring 126 which 100 presses against the pin 124 as well as being tensioned for removably holding the tapered free end of the pawl 122 normally in the wedge shaped socket 120 of the housing. The pawl 123 is likewise in the form of a 105 curved tapered short bar having one of its ends rotatably mounted on a pin 127 held in the upper part of the plate 34 of the partition 30 of the casing. The tapered free end of the pawl is normally held removably 110 in socket 121 of the housing under the tension of a spring 128 which is seated in a socket, as 129, provided lengthwise of the pawl so that the spring 128 presses against the pin 127. On the end of the pin 118 protruding exteriorly of the housing is fulcrumed a lever or locking element, as 130. This lever is preferably in the form of a 115 curved bar having a head or end portion, as 131, terminating in closely spaced proximity to the pawl 122, and the other end portion, as 132, terminates on a line corresponding with the central part of the curved slot 119 of the side wall 108 of the housing. On the free end of the portion 132 of the lock- 120 125 130 135

10 The flange 111 is revolvably disposed through the opening 35 of the plate 34 which is fixed to the partition 31 of the casing, and the housing may be held in movable contact with the plate 34 by a collar 115 120 which is fastened, as at 116, on the end of 130

ing element or lever 130 is an angularly disposed lug or finger 133 which extends into the housing through the slot 119, and in the free end of the lug is a groove, as 134. Fig. 2, in which part of the spring 106 is slidably arranged. When the spring actuating means 43 is "run-down" by the spring being unwrapped or unwound on the sleeve member 44 of the clutch 45 the locking element or lever 130 will be in the position shown in Fig. 4 with its end portion or head 130 in closely spaced relation to the pawl 122. The spring 106 being fastened to the sleeve member 44 as well as being held to the housing 107, the spring will be tensioned by winding on the sleeve member with rotation from right to left of the gear 52 and the bevel gear 51 when the driving means 42 is driven by the drive member 79, as above explained, the pawl 122 then serves to prevent rotation of the housing 107, and with the winding of the spring the end portion 132 with the lug 133 of the locking element or lever 130 will move with the spring toward the sleeve member 44 of the clutch 45. The head or end portion 131 of the lever will then move into contact with the pawl 122 which will be swung clear from the socket 120 of the housing with the complete winding of the spring 106. The spring and housing will then revolve with rotation of the clutch 45 by the driving of the bevel gear 51 and gear 52. In event of separation of the driving parts 42 from the parts 39 of the mechanism 38 and with the slidable adjustment of the shaft 48 inwardly of the boss 29 of the section 15 of the casing by the spring action of the bar 99, plate 95, roller 96 and collars 97, 98, as above explained, the sleeve member 46 of the clutch 45 will be separated from the sleeve member 47 of the clutch against the tension of the spring 50 of the shaft 48. The tension of the spring 106 will then cause the sleeve member 44 of the clutch 45 with the bevel gear 51 and gear 52 of the parts 39 of the mechanism to reversely operate independently of the operation of the driving parts or means 42 for sounding alarm by the parts 39 operating the parts 40 and 41 of the mechanism, as hereinbefore explained. With the operation of these parts of the spring actuating means 43 the housing will be held against rotation by the pawl 123, in order to allow the spring 106 when tensioned to effectually actuate.

The operation of the mechanism 38 for sounding the alarm 36 and for preventing the alarm from being sounded is regulated by a controller, as 135, which is operative according to a determined adjustment for controlling or adjusting or locking the mechanism so that the parts 40 will be disconnected from the parts 41 to prevent the alarm from normally sounding when the mechanism is operated by the drive member

79. The controller is also operative according to a different adjustment for readjusting or unlocking the mechanism whereby the parts 40 will be connected to the parts 41 to cause sounding of the alarm with the operation of the mechanism by the drive member. When the device is applied to an automobile, autotruck or like vehicle it is preferably mounted for being operated by a drive member associated with the transmission or engine which usually rotates in one direction whether the vehicle is moving forwardly or backwardly. The controller 135 may be of any appropriate type, though the form of the controller illustrated has a shaft 136 one end of which is rotatably disposed in a bore in the fixed bracket 30 within the casing 10, and the other end portion of the shaft is journaled in the bearing 28 of the section 14 of the casing. The shaft 136 is of a length so that it may protrude a suitable distance exteriorly of the casing. On the central part of the shaft 136 within the casing are a number of drums, such as an inner drum 137, an intermediate drum 138 and an outer drum 139, all in relative nesting arrangement. These drums are preferably of approximately cup-shapes or cap-shapes to provide each with a bottom wall 140 and an annular side wall or flange 141. The drums are of relative sizes so that their bottom walls and side walls are spaced from each other, and the drums are also arranged so that the free edges of their side walls are on similar relative planes as well as being disposed whereby the locking lug 71 of the head 70 of the shaft 66 of the parts 41 of the mechanism 38 may be moved into and out of contact with the free edges of the side walls of all of the drums. The inner drums 137 has a hub or bearing 142 through which the shaft 136 is disposed, and this drum is revolvable with the rotation of the shaft by the hub 142 being fastened, at 143, to the shaft. The intermediate drum 138 has a hub or bearing 144 through which the shaft 136 is also disposed, and this intermediate drum is preferably freely revolvable on the shaft. One end of the hub 144 of the intermediate drum movably contacts with the hub 142 of the inner drum 137, and the hub 144 is of a length so that its other end extends through a hub or bearing 145 provided on the outer drum 139. The outer drum 139 is thereby freely revolvable on the hub 144 of the intermediate drum. On the outer face at the marginal edge of the bottom wall 140 of the outer drum 139 is held, at 146, an internal gear 147, and in mesh with this internal gear is a pinion 148 which is revolvable on a pin or stud 149 held in the bottom wall 140 of the outer drum 139. The pinion 148 is also in mesh with a gear 150 which is freely revolvable on the shaft 136, and fixed to this gear 150 is a circular plate 151 of

considerably greater diameter than the gear. On the shaft 136 between the plate 151 and the bearing 28 of the section 14 of the casing 10 is held, at 152, one end of a bracket 5 bar or lever 153 having on its other end a recessed head or boss 154 disposed so that the edge of the wall of the recess is in movable contact with the plate 151 at its outer edge part. In the recess of the boss 154 is 10 a pawl, as 155, having one of its ends slidably movable in a hole in the bottom of the boss, and in the recess is a spring, as 156, which is tensioned for normally forcing the pawl 155 outwardly of the recess and into 15 movable contact with the plate 151. In the exposed face of the plate 151 at part of its marginal edge is an elongated socket 157 which is so disposed as well as being of a size adapted to receive the pawl 155, and 20 this socket extends lengthwise of the circumference of the plate besides being tapered inwardly of the plate in a wedge shape so that when the shaft 136 and the bracket bar 153 are rotatably adjusted from right to left 25 sufficient distance the pawl 155 will be yieldingly forced by the spring 156 into the socket 157 for engaging the end wall of the socket at its greatest depth. The plate 151, gear 150, pinion 148, internal gear 147 and 30 the outer drum 139 will then be rotatably adjusted independently of the drums 137 and 138 according to the further rotatable adjustment of the shaft 136 and the bracket bar 153. In the bottom wall 140 of the 35 inner drum 137 adjacent to the side wall 141 is a boss, as 158, having the entrance to its recess in opposition to the bottom wall of the intermediate drum 138. In the recess of the boss 158 is a movable pawl, as 40 159, which is under the tension of a spring, as 160, provided in the recess for normally forcing the pawl outwardly of the recess and into movable engagement with the inner face of the bottom wall 140 of the intermediate drum. In part of the inner face of 45 the bottom wall 140 of the intermediate drum 138 is an elongated socket 161 which is so disposed as well as being of a size adapted to receive the pawl 159, and this socket extends lengthwise of the circumference of the bottom wall of the intermediate drum besides being tapered inwardly of the bottom wall in a wedge shape in an opposite direction relative to the taper of the socket 157 50 of the plate 151 so that when the shaft 136 and the inner drum 137 are rotatably adjusted from left to right sufficient distance the pawl 159 will be yieldingly forced by the spring 160 into the socket 161 for engaging the end wall of the socket at its greatest depth. The intermediate drum 138 will 55 then be rotatably adjusted with the further adjustment of the inner drum 157 and the shaft 136. In part of the free edge of the 60 side wall 141 of the inner drum 137 is a cam notch 162 of a semi-elliptic shape, and in part of the free edge of the side wall 141 of the intermediate drum 138 is an angular notch, as 163, while in part of the free edge of the side wall 141 of the outer drum 139 is also an angular notch, as 164. The notches 162, 163, 164 are of sizes adapted to receive the locking lug 71 of the shaft 66 of the parts 41 of the mechanism 38, and as the locking lug is preferably of an angular shape the intermediate drum 138 and the outer drum 139 will be prevented from rotation when the locking lug is seated in the notches 163 and 164, while the cam notch 162 of the inner drum being curved this inner drum may be rotated for forcing the locking lug 71 from the cam notch as well as forcing the locking lug from the notches of the intermediate drum and outer drum. The notches 162, 163, 164 of the drums are 70 relatively arranged so that they will be in register for receiving the locking lug 71 of the shaft 66 when the shaft 136, bracket bar 153 and inner drum 137 are rotatably adjusted for seating the pawl 155 of the bracket bar and seating the pawl 159 of the inner drum in the socket 157 of the plate 151 and in the socket 161 of the intermediate drum. In order to rotatably hold the drums 137, 138, 139 as well as holding the shaft 136 75 against liability of accidentally moving when adjusted in determined positions, a friction brake, as 165, is provided. This brake preferably consists of a head or boss, as 166, which extends from the fixed bracket 80 30 within the casing 10 toward the drums 137, 138, 139, and the free end of the head terminates in spaced relation to the aligned free edges of the side walls 141 of the drums. In the head 166 are three corresponding spaced recesses 167 provided so that their entrances are in opposition to the free edges of the side walls of the drums. Movable inwardly and outwardly of the entrances of the recesses of the head or boss 166 are three shoes 168, 169, 170 all of which are preferably in the forms of blocks or pins in movable engagement with the free edges of the side walls of the drums, and all of these shoes or blocks are larger than the cam notch 162 as well as being larger than the notches 163 and 164 of the drums to prevent the shoes from entering the notches when the drums are revolvably adjusted. 105 In the recesses 167 of the head or boss 166 are springs 171 which bear against the bottoms of the recesses and against the brake shoes or blocks, and these springs normally serve to force the blocks frictionally into yielding contact with the side walls of the drums with sufficient pressure to prevent the drums and the shaft 136 from tendency to shift when adjusted in determined relative positions. The shaft 136 110 may lead to any suitable support, as 172, 130

such as the dash board of the body of a vehicle when the device is applied thereon, in order that the device may be accessible for adjustment, and the shaft 136 with the drums 137, 138, 139 may be adjusted according to a determined adjustment for locking and unlocking the mechanism 38 by providing any suitable means, though in the drawings is illustrated a key element, as 173. 10 This key element has a circular disk, as 174, which is secured, at 175, on the support 172, and in this fixed disk as well as in the support are registered openings 176 through which the shaft 136 rotatably extends. On 15 the shaft 136 is held a second circular disk or dial, as 177, having a knurled marginal edge portion, as 178, to permit the disk to be readily rotated manually for rotating the shaft 136. On part of the disk 174 is provided a symbol or mark, as 179, for 20 serving as a guide to indicate determined positions to which the dial 177 may be rotated. On the marginal edge of the dial 177 adjacent the disk 174 is an annular 25 scale 180 divided into equidistant sections, as 181, which may be suitably numbered, as shown, and each section may be subdivided into parts representing points or degrees, as 182. The characters of the sections 181 and the characters of the subdivisions 182 of the dial 177 are adapted to 30 register with the guide symbol 179 of the disk 174 when the dial is revolvably adjusted accordingly for revolvably adjusting 35 the shaft 136. By varying the position of the intermediate drum 138 on the shaft 136 relative to the position of the inner drum 137, and by varying the relative sizes of the pinion 148 and gear 150 as well as varying 40 the position of the plate 151 a multiplicity of adjustments may be provided whereby it will require the dial 177 to be turned one or a number of complete revolutions or parts of revolutions in different directions 45 according to secret "combinations" in order to revolve the drums to cause the pawl 159 of the inner drum 137 to be inserted in the socket 161 of the intermediate drum 138 and to cause the pawl 155 of the arm 153 to be seated in the socket 157 of the plate 151 of 50 the outer drum 139 for registering the cam notch 162 with the notches 163 and 164 of the drums, as above explained, the completion of each step in the revolvably adjusting of the dial being indicated by one of the character sections 181 or one of the character subdivisions 182 being registered with the guide symbol 179 of the disk 174. With 55 the adjustment of the dial 177 and the shaft 136 for registering the notches 162, 163, 164 the drums will also be positioned so that the notches are in the path of movement of the locking lug 71 of the shaft 66 of the parts 41 of the mechanism 38. The tension 60 of the spring 72 of the shaft will then force

the locking lug 71 into the registered notches of the drums, and with this movement of the shaft 66 its cam sleeve 74 will be separated from its engagement with the finger 62 of the alarm sounding parts 40 70 of the mechanism 38. With this locking of the mechanism the parts 39 of the mechanism may then be operated by the driving of the drive member 79 without causing sounding of the alarm. To cause the alarm 75 to be sounded with the driving of the drive member 79 the dial 177 of the key element is revolvably adjusted so that the inner drum 137 will be rotatably adjusted whereby the curved edges of the cam notch 162 80 will force the locking lug 71 of the shaft 66 from its position in the notches of all of the drums against the tension of the spring 72. This reverse movement of the shaft 66 will cause the cam sleeve 74 of this shaft to 85 move into engagement with the finger 62 of the alarm sounding parts 40 of the mechanism. In event of the drive member 79 being driven the parts 39 of the mechanism will be operated to cause operation of the parts 41 with the parts 40 for sounding the alarm, as hereinbefore explained. Thus where the device is applied to a movable body, such as a vehicle, the mechanism 38 may be releasably locked by the controller 90 95 135 being operated according to a determined adjustment to allow the vehicle to be driven by an authorized person, and by operating the controller for unlocking the mechanism the alarm will be sounded by 100 the operation of the vehicle, in event of the vehicle being moved when at a standstill, such as when parked or garaged. The dial 177 of the key element 173 and the shaft 136 may be releasably locked by any suitable means, if desired, to prevent the dial from accidentally moving or being tampered with when the controller 135 is in an adjusted position, though in the drawings is 105 illustrated a locking device, as 183. This locking device has a collar, as 184, fixed on part of the shaft 136 of the controller in the opening 176 of the support 172 so that the collar abuts against the disk 174 of the key element 173. The shaft 136 protrudes 110 beyond the dial 177 of the key element, and this protruding end is exteriorly threaded. On the threaded end of the shaft is a nut, as 185, which is adapted to be screwed into 115 releasable engagement with the dial 177 for locking the dial and shaft against accidental movement when adjusted, and by 120 reversely rotating the nut the dial and shaft will be released for permitting the controller to be operated. 125 While we have illustrated and described the parts of the controller 135 in this present application we have not made claim to the specific parts thereof as said parts are disclosed and claimed in our application or a 130

patent, serially numbered 607,127, filed December 15, 1922. Moreover, the term movable body as used herein, may include the doors of safes, buildings and elsewhere, and the term vehicle may include any travelling conveyance.

While in the foregoing description we have embodied an illustrative form of our invention, we do not wish to be understood

as limiting ourselves thereto, as we are aware that modifications may be made therein without departing from the principle or sacrificing any of the advantages of this invention, therefore, we reserve to ourselves the right to make such changes as fairly fall within the scope of the invention.

Having thus described our invention, we claim as new and desire to secure by Letters Patent:-

1. In a safety device for a movable body, in combination, an alarm adapted to be mounted on the body, means adapted to be driven by the body when in motion, mechanism detachably connected to the driven means for being operated to sound the alarm, said mechanism adapted to be releasably locked against normally sounding the alarm when the body is in motion and when unlocked the mechanism adapted to be operated for sounding the alarm by the operation of the driven means with movement of the body and spring actuating means operative for independently operating the mechanism with its separation from the driven means to cause sounding of the alarm.

2. In a safety device for a movable body, in combination, an alarm adapted to be mounted on the body, a shaft adapted to be driven by the body when in motion, mechanism detachably connected to and operative by the driven shaft said mechanism having parts for sounding the alarm, adapted to be adjusted into inaction for normally preventing the alarm from sounding when the body is in motion and the parts adapted to be readjusted for operating to sound the alarm by the operation of the driven shaft with movement of the body, and spring actuating means operative for independently operating the mechanism with its separation from the driven shaft to cause sounding of the alarm.

3. In a safety device for a movable body, in combination, an alarm adapted to be mounted on the body, means adapted to be driven by the body when in motion, mechanism detachably connected to and operative by the driven means, said mechanism having parts adapted to be disconnected from the other parts thereof for normally cutting-out the alarm when the body is in motion and the separated parts adapted to be reconnected to the other parts whereby the mechanism will operate to sound the

alarm by the operation of the driven means with movement of the body permutation means for controlling the selective disconnecting and reconnecting operations of said parts of the mechanism, and spring actuating means operative for independently operating the mechanism with its separation from the driven means to cause sounding of the alarm.

4. In a safety device for a vehicle, in combination, a casing adapted to be mounted on the vehicle, an alarm in the casing, means in the casing, adapted to be operated by a drive member of the vehicle, lockable mechanism in the casing, operative by said driven means for sounding the alarm, a shaft journaled in the casing rotative according to different adjustments, and controlling means operative with the rotation of the shaft for selectively locking the mechanism against normally sounding the alarm when the vehicle is driven and the controlling means also being operative with the rotation of the shaft to selectively unlock the mechanism for operating to sound the alarm by the operation of the driven means with movement of the vehicle, and permutation means on the shaft for controlling the selective adjustments of said shaft.

5. In a safety device for a vehicle, in combination, a casing adapted to be mounted on the vehicle, an alarm in the casing, means in the casing, adapted to be operated by a drive member of the vehicle, gearing in the casing, operative by the driven means, adjustable means in the casing, operative by the gearing for sounding the alarm, a shaft in the casing, adapted to be rotated according to different determined adjustments, and controlling means operative with the rotation of the shaft for selectively adjusting the adjustable means to prevent sounding the alarm when the vehicle is driven and the controlling means also being operative with the rotation of the shaft to selectively readjust said adjustable means for sounding the alarm with the operation of the mechanism by the driven means operating with movement of the vehicle, and permutation means on the shaft for controlling the selective adjustments of said shaft.

6. In a safety device for a vehicle, in combination, a casing adapted to be mounted on the vehicle, an alarm in the casing, means in the casing, adapted to be operated by a drive member of the vehicle, mechanism detachably connected to the driven means for being operated to sound the alarm, said mechanism adapted to be releasably locked against normally sounding the alarm when the vehicle is driven and when unlocked the mechanism adapted to be operated for sounding the alarm by the operation of the driven means with movement of the vehicle, a spring in the casing, adapted to be ten-

- sioned with the operation of said driven means whereby the alarm sounding mechanism will operate with its separation from the driven means, and locking means in the 5 casing, operative with the tensioning of the spring to check the action of the spring when under a determined tension, said locking means also being operative with the separation of the alarm sounding mechanism 10 from the driven means to release the tensioned spring whereby the alarm sounding mechanism will operate independently of the operation of the driving means to sound the alarm.
- 15 7. In a safety device for a vehicle, in combination, a casing adapted to be mounted on the vehicle, an alarm in the casing, means in the casing, adapted to be operated by a drive member of the vehicle, mechanism in the casing, detachably connected to and operative by the driven means for being operated to sound the alarm, controlling means operative according to different determined adjustments for releasably locking 20 the mechanism against normally sounding the alarm when the vehicle is driven and the controlling means being operative to unlock the mechanism for operating to sound the alarm by the operation of the 25 driven means with movement of the vehicle, a spring in the casing, adapted to be tensioned with the operation of said driven means whereby the alarm sounding mechanism will operate with its separation from 30 the driven means, and locking means in the casing, operative with the tensioning of the spring to check the action of the spring when under a determined tension, said locking means also being operative with the 35 separation of the alarm sounding mechanism from the driven means to release the tensioned spring whereby the alarm sounding mechanism will operate independently of the operation of the driven means to sound the alarm, and permutation means operative for controlling the selective 40 adjustments of the controlling means.
- 45 8. In a safety device for a vehicle, in combination, a casing adapted to be mounted on the vehicle, an alarm in the casing, means in the casing, adapted to be operated by a drive member of the vehicle, mechanism in the casing, detachably connected to and operative by the driven means, said mechanism having adjustable parts for sounding 50 the alarm, controlling means operative according to a determined adjustment for adjusting the adjustable parts of the mechanism into inaction to prevent sounding the 55 alarm when the vehicle is driven and the controlling means being operative to readjust said parts for operating to sound the alarm by operation of the mechanism with movement of the vehicle, a spring in the 60 casing, adapted to be tensioned with the 65

operation of said driven means whereby the alarm sounding mechanism will operate with its separation from the driven means, and locking means in the casing, operative 70 with the tensioning of the spring to check the action of the spring when under a determined tension, said locking means also being operative with the separation of the alarm sounding mechanism from the driven means to release the tensioned spring whereby the alarm sounding mechanism with its 75 adjustable parts will operate independently of the operation of the driven means to sound the alarm.

9. In a safety device for a vehicle, in combination, a casing adapted to be mounted on the vehicle, an alarm in the casing, means in the casing, operative for sounding the alarm, including a trip, a slidable shaft in the casing, having a locking bolt, a cam rotatable on the shaft and movable into and out of engagement with the trip of the alarm sounding means with the slidable movement of the shaft when its bolt is locked and unlocked, controlling means in the casing, adjustable according to a determined adjustment for locking and unlocking the bolt to slidably adjust the shaft for moving the cam into and out of engagement with the trip of the alarm sounding means, and gearing in the casing, operative by the vehicle when in motion for rotating the cam on the slidable shaft when adjusted by the unlocking of its bolt with the unlocking adjustment of the controlling means.

10. In a safety device for a vehicle, in combination, a casing adapted to be mounted on the vehicle, an alarm in the casing, means in the casing, operative for sounding the alarm, including a trip, a slidable shaft in the casing, having a locking bolt, a cam rotatable on the shaft and movable into and out of engagement with the trip of the alarm sounding means with the slidable movement of the shaft when its bolt is locked and unlocked, controlling means in the casing, adjustable according to a determined adjustment for locking and unlocking the bolt to slidably adjust the shaft for moving the cam into and out of engagement with the trip of the alarm sounding means, a driven shaft journaled in and also slidable inwardly and outwardly of the casing, means operative by a drive member of the vehicle when in motion for driving the driven shaft, and gearing in the casing, operative by the driving of the driven shaft for rotating the cam on the slidable shaft when adjusted by the unlocking of its bolt with the unlocking adjustment of the controlling means.

11. In a safety device for a vehicle, in combination, a casing adapted to be mounted on the vehicle, an alarm in the casing, means in the casing operative for sounding

the alarm, including a trip, a slidable shaft in the casing, having a locking bolt, a cam rotatable on the shaft and movable into and out of engagement with the trip of the 5 alarm sounding means with the slidable movement of the shaft when its bolt is locked and unlocked, controlling means in the casing, adjustable according to different determined adjustments for locking and un- 10 locking the bolt to slidably adjust the shaft for moving the cam into and out of engagement with the trip of the alarm sounding means, a driven shaft journaled in and also slidable inwardly and outwardly of the cas- 15 ing, means operative by a drive member of the vehicle when in motion for driving the driven shaft, gearing in the casing, operative by the driving of the driven shaft for rotating the cam on the slidable shaft when 20 adjusted by the unlocking of its bolt with the unlocking adjustment of the controlling means and said gearing being detachable from the driven shaft, means operative for locking the driven shaft to the casing when 25 separated from the gearing, and permutation means operative for controlling the selective adjustments of the controlling means.

12. In a safety device for a vehicle, in combination, a casing adapted to be mounted 30 on the vehicle, an alarm in the casing, means in the casing, operative for sounding the alarm, including a trip, a slidable shaft in the casing, having a locking bolt, a cam rotatable on the shaft and movable into and 35 out of engagement with the trip of the alarm sounding means with the slidable movement of the shaft when its bolt is locked and unlocked, controlling means in the casing, adjustable according to a deter- 40 mined adjustment for locking and unlock- ing the bolt to slidably adjust the shaft for moving the cam into and out of engagement with the trip of the alarm sounding means, a driven shaft journaled in and also slidable 45 inwardly and outwardly of the casing, means operative by a drive member of the vehicle when in motion for driving the driven shaft, gearing in the casing, operative by the driving of the driven shaft for 50 rotating the cam on the slidable shaft when adjusted by the unlocking of its bolt with the unlocking adjustment of the controlling means and said gearing being detachable from the driven shaft, and spring actuating means, operative with the detaching of the gearing from the driven shaft for operating the gearing independently of movement of the vehicle.

13. In a safety device for a vehicle, in combination, a casing adapted to be mounted 60 on the vehicle, an alarm in the casing, means in the casing, operative for sounding the alarm, including a trip, a slidable shaft in the casing, having a locking bolt, a cam ro- 65 tatable on the shaft and movable into and

out of engagement with the trip of the alarm sounding means with the slidable movement of the shaft when its bolt is locked and unlocked, controlling means in the casing, adjustable according to a determined adjustment for locking and unlocking the bolt to slidably adjust the shaft for moving the cam into and out of engagement with the trip of the alarm sounding means, a driven shaft journaled in and also slidable inwardly and outwardly in the casing, means operative by a drive member of the vehicle when in motion for driving the driven shaft, gearing in the casing, operative by the driving of the driven shaft for rotating the cam on the 70 slidable shaft when adjusted by the unlock- ing of its bolt with the unlocking adjustment of the controlling means and said gearing being detachable from the driven shaft, means operative for locking the driven shaft to the casing when separated from the 75 gearing, and spring actuating means, operative with the detaching of the gearing from the driven shaft for operating the gearing independently of movement of the vehicle.

14. In a safety device, in combination, an alarm, a driven slidable shaft, a clutch including two sleeve members on the shaft, one of the members held to the shaft and the other member freely revolvable on the shaft, both of said sleeve members being releasably engaged for simultaneous rotation with the driving of the shaft in one direction and with the slidable movement of the shaft the member held thereon will be released from the freely revolvable member, mechanism operative with the driving of the freely revolvable sleeve member for causing the sound of the alarm, a housing surrounding the members of the clutch and releasably locked to the sleeve member held to said shaft, a convoluted spring within the housing, said spring having one of its ends held to the freely revolvable sleeve member and having its other end held to the housing, means releasably engaging the housing to check the rotation of the housing when the freely revolvable sleeve member is driven for winding the spring, means on the housing, operative by the spring with its winding movement for releasing the engagement with the housing of said checking means, and means releasably engaging the housing to check the rotation of the housing with the 100 slidable movement of the driven shaft for 105 releasing the sleeve member held thereto from the housing whereby the spring will 110 unwind so that its tension will drive the freely revolvable sleeve member for operating the mechanism to cause sounding of the 115 alarm.

15. In a safety device, in combination, an alarm, a driven slidable shaft, a clutch including two sleeve members on the shaft, one of the members held to the shaft and the 120

other member freely revolvable on the shaft, both of said sleeve members being releasably engaged for simultaneous rotation with the driving of the shaft in one direction and with the slidable movement of the shaft the member held thereon will be released from the freely revolvable member, mechanism operative with the driving of the freely revolvable sleeve member for causing the sounding of the alarm, a housing surrounding the members of the clutch and releasably locked to the sleeve member held to said shaft, a convoluted spring within the housing, said spring having one of its ends held to the freely revolvable sleeve member and having its other end held to the housing, a pawl releasably engaging the housing to check the rotation of the housing when the freely revolvable sleeve member is driven for winding the spring, a lever fulcrumed to the housing, operative by the spring with its winding movement for releasing the engagement with the housing of said checking means, and a second pawl releasably engaging the housing to check the rotation of the housing with the slidable movement of the driven shaft for releasing the sleeve member held thereto from the housing whereby the spring will unwind so that its tension will drive the freely revolvable sleeve member for operating said mechanism to cause sounding of the alarm.

16. In a safety device, in combination, an alarm, a driven slidable shaft, a clutch including two sleeve members on the shaft, one of the members held to the shaft and the other member freely revolvable on the shaft, both of said sleeve members being releasably engaged for simultaneous rotation with the driving of the shaft in one direction and with the slidable movement of the shaft the member held thereon will be released from the freely revolvable member mechanism operative with the driving of the freely revolvable sleeve member for causing the sounding of the alarm, a housing surrounding the members of the clutch and releasably locked to the sleeve member held to said shaft, a convoluted spring within the housing, said spring having one of its ends held to the freely revolvable sleeve member and having its other end held to the housing, means releasably engaging the housing to check the rotation of the housing when the freely revolvable sleeve member is driven for winding the spring, means on the housing, operative by the spring with its winding movement for releasing the engagement with the housing of said checking means, means releasably engaging the housing to check the rotation of the housing with the slidable movement of the driven shaft for releasing the sleeve member held thereto from the housing whereby the spring will unwind so that its tension

will drive the freely revolvable sleeve member for operating said mechanism to cause sounding of the alarm, and controlling means operative according to a determined adjustment for releasably locking the mechanism against normally sounding the alarm when the mechanism is operated and the controlling means being operative to unlock the mechanism whereby its operation will cause sounding of the alarm. 70

17. In a safety device, in combination, an alarm, a driven slidable shaft, a clutch including two sleeve members on the shaft, one of the members held to the shaft and the other member freely revolvable on the shaft, both of said sleeve members being releasably engaged for simultaneous rotation with the driving of the shaft in one direction and with the slidable movement of the shaft the member held thereon will be released from the freely revolvable member, mechanism operative with the driving of the freely revolvable sleeve member for causing the sounding of the alarm, a housing surrounding the members of the clutch and releasably locked to the sleeve member held to said shaft, a convoluted spring within the housing, said spring having one of its ends held to the freely revolvable sleeve member and having its other end held to the housing, a pawl releasably engaging the housing to check the rotation of the housing when the freely revolvable sleeve member is driven for winding the spring, a lever fulcrumed to the housing, operative by the spring with its winding movement for releasing the engagement with the housing of said checking means, a pawl releasably engaging the housing to check the rotation of the housing with the slidable movement of the driven shaft for releasing the sleeve member thereto from the housing whereby the spring will unwind so that its tension will drive the freely revolvable sleeve member for operating said mechanism to cause sounding of the alarm, and controlling means operative according to a determined adjustment for releasably locking the mechanism against normally sounding the alarm when the mechanism is operated and the controlling means being operative to unlock the mechanism whereby its operation will cause sounding of the alarm. 75 80 90 95

18. A spring actuating mechanism for operating an alarm and other mechanisms, comprising a driven sleeve member, a housing surrounding the driven member, a convoluted spring within the housing, said spring having one of its ends held to the driven member and having its other end held to the housing, means releasably engaging the housing to check the rotation of the housing when the driven member is rotated for winding the spring, means on the housing, operative by the spring with 100 105 110 115 120 125 130

its winding movement for releasing the engagement with the housing of said checking means, and means releasably engaging the housing to check the rotation of the housing with the unwinding of the spring for driving the driven member.

19. A spring actuating mechanism for operating an alarm and other mechanisms, comprising a driven sleeve member, a housing surrounding the driven member, a convoluted spring within the housing, said spring having one of its ends held to the driven member and having its other end held to the housing, a pawl releasably engaging the housing to check the rotation of the housing when the driven member is rotated for winding the spring, a lever fulcrumed to the housing, operative by the spring with its winding movement for releasing the engagement with the housing of said checking means, and a pawl releasably engaging the housing to check the rotation of the housing with the unwinding of the spring for driving the driven member.

20. A safety device as characterized, comprising a casing adapted to be mounted on a movable body, an alarm in the casing, a rotative member in the casing, slidably movable inwardly and outwardly of the casing and adapted to be driven by the body when in motion, means in the casing operative with the separation of the casing from the body for causing the rotative member to be moved outwardly of the casing, and spring actuated mechanism in the casing, detachably connected to the rotative member and operative with the driving of the rotative member for sounding the alarm, said mechanism having adjustable parts adapted to be controlled according to different determined adjustments for preventing the mechanism from sounding the alarm when operated by the operation of the rotative member when the body is moved and said parts being controllable according to selective readjustments to cause the alarm to sound with the operation of the mechanism by the driving of the rotative member with movement of the body and the mechanism being self-operative to sound the alarm with its separation from the rotative member when moved outward of the casing by the actuation of said means.

21. A safety device as characterized, comprising a casing adapted to be mounted on a movable body, an alarm in the casing, a rotative member in the casing, slidably movable inwardly and outwardly of the casing and adapted to be driven by the body when in motion, means in the casing operative with the separation of the casing from the body for causing the rotative member to be moved outwardly of the casing, spring actuated mechanism in the casing, detachably connected to the rotative member and oper-

ative with the driving of the rotative member for sounding the alarm, said mechanism having adjustable parts adapted to be controlled according to different determined adjustments for preventing the mechanism from sounding the alarm when operated by the operation of the rotative member when the body is moved and said parts being controllable according to selective readjustments to cause the alarm to sound with the operation of the mechanism by the driving of the rotative member with movement of the body and the mechanism being self-operative to sound the alarm with its separation from the rotative member when moved outward of the casing by the actuation of said means, and locking means operative by the outward movement of the rotative member for preventing reverse adjustment of said member inwardly of the casing.

22. A safety device as characterized, comprising a casing adapted to be mounted on a movable body, an alarm in the casing, a rotative member in the casing, slidably movable inwardly and outwardly of the casing and adapted to be driven by the body when in motion, means in the casing operative with the separation of the casing from the body for causing the rotative member to be moved outwardly of the casing, and spring actuated mechanism in the casing, detachably connected to the rotative member and operative with the driving of the rotative member for sounding the alarm, said mechanism having adjustable parts adapted to be controlled according to different determined adjustments for preventing the mechanism from sounding the alarm when operated by the operation of the rotative member when the body is moved and said parts being controllable according to selective readjustments to cause the alarm to sound with the operation of the mechanism by the driving of the rotative member with movement of the body and the mechanism being self-operative to sound the alarm with its separation from the rotative member when moved outward of the casing by the actuation of said means, and permutation means operative for controlling the selective adjustments of the adjustable parts of the mechanism.

23. A safety device as characterized, comprising a casing adapted to be mounted on a movable body, an alarm in the casing, a rotative member in the casing, slidably movable inwardly and outwardly of the casing and adapted to be driven by the body when in motion, means in the casing operative with the separation of the casing from the body for causing the rotative member to be moved outwardly of the casing, and spring actuated mechanism in the casing, detachably connected to the rotative member and operative with the driving of the rotative member for sounding the alarm, said mechanism

having adjustable parts adapted to be controlled according to different determined adjustments for preventing the mechanism from sounding the alarm when operated by the operation of the rotative member when the body is moved and said parts being controllable according to selective readjustments to cause the alarm to sound with the operation of the mechanism by the driving of the rotative member with movement of the body and the mechanism being self-operative to sound the alarm with its separation from the rotative member when moved outward of the casing by the actuation of said means, locking means operative by the outward movement of the rotative member for preventing reverse adjustment of said member inwardly of the casing, and permutation means operative for controlling the selective adjustments of the adjustable parts of the mechanism.

24. A safety device as characterized, comprising a casing adapted to be mounted on a movable body, an alarm in the casing, a rotative member in the casing, slidably movable inwardly and outwardly of the casing and adapted to be driven by the body when in motion, means in the casing operative with the separation of the casing from the body for causing the rotative member to be moved outwardly of the casing, means in the casing, operative for sounding the alarm, and spring actuated mechanism in the casing, detachably connected to the rotative member and operative with the driving of the rotative member, said mechanism including a locking bolt adjustable for controlling the operation of the alarm sounding means for preventing sounding of the alarm when the mechanism is operated by the rotative member when the body is moved and said bolt being controllable according to selective readjustments to cause the alarm to sound with the operation of the mechanism by the driving of the rotative member with movement of the body and the mechanism being self-operative to cause the bolt to operate the alarm sounding means for giving an alarm with its separation from the rotative member when moved outward of the casing by the actuation of said means, and permutation means in the casing adjustable according to different determined adjustments for selectively adjusting the bolt.

25. A safety device as characterized, comprising an alarm, rotative means, mechanism detachably connected to and operative by the rotative means for sounding the alarm, said mechanism including a shiftable bolt engageable for preventing the mechanism from sounding the alarm with its operation and the bolt being disengageable for causing the mechanism with its operation to sound the alarm, and spring

actuated means for independently operating the mechanism when detached from the rotative means, and controlling means adjustable according to different determined adjustments for engaging and disengaging said bolt whereby the operation of the mechanism may be selectively controlled. 70

26. A safety device as characterized, comprising a casing, an alarm in the casing, mechanism in the casing, including detachable means adapted to be driven by a movable body when in motion for operating the mechanism to sound the alarm at intervals, spring actuating means independently operating the driven means for operating the mechanism with its separation from the driven means to cause sounding of the alarm, and controlling means in the casing adjustable according to a plurality of different determined adjustments whereby the 80 operation of the mechanism will be selectively controlled for causing the alarm to sound with the driving of the driven means by the body when moved and for also preventing the mechanism from sounding the 85 alarm when the body is in motion. 90

27. A safety device as characterized, comprising a casing, an alarm in the casing, mechanism in the casing adapted to be separated by a movable body when in motion, 95 including a locking bolt controlling the operation of the mechanism to sound the alarm at intervals, and simultaneously rotative members in the casing variably adjustable when rotated in unison according to different determined adjustments for locking and unlocking the bolt whereby the mechanism will sound the alarm when the body is moved and subsequently prevent sounding the alarm with movement of the body. 100

28. A safety device as characterized, comprising a casing, an alarm in the casing, mechanism in the casing adapted to be operated by a movable body when in motion, including a locking bolt controlling the operation of the mechanism to sound the alarm at intervals, simultaneously rotative members in the casing variably adjustable when rotated according to different determined adjustments for locking and unlocking the 115 bolt whereby the mechanism will sound the alarm when the body is moved and subsequently prevent sounding the alarm with movement of the body, a shaft journaled in the casing for rotatively adjusting the members in unison, and permutation means on the shaft for controlling the selective adjustments of the shaft and said rotative members. 120

29. A safety device as characterized, comprising a casing, sound emitting means in the casing, mechanism in the casing, including a detachable shaft adapted to be driven by a movable body when in motion for operating the mechanism to operate the sound 130

emitting means at intervals, spring actuating means independently operative of the driven shaft for operating the mechanism with its separation from the driven shaft to cause the sound emitting means to operate, and controlling means in the casing adjustable according to a plurality of different determined adjustments whereby the operation of the mechanism will be selectively controlled for causing the sound emitting means to operate with the driving of the driven shaft by the body when moved and for also preventing the mechanism from operating the sound emitting means when the body is in motion.

30. The combination, in a safety device, with a bell and a shaft adapted to be driven by a movable body when in motion, of bell ringing mechanism operative by the driving of the shaft and having parts adjustable for preventing ringing the bell when the body is in motion and the parts being readable for causing the bell to ring with movement of the body, and simultaneously rotative members variably adjustable when rotated according to different determined adjustments for controlling the adjusting of the adjustable parts whereby the mechanism will ring the bell and subsequently prevent ringing the bell with the driving of the driven shaft by movement of the body.

31. The combination, in a safety device, with a bell and a shaft adapted to be driven by a movable body when in motion, of bell ringing mechanism detachably connected to and operative by the driving of the driven shaft, said mechanism having parts adjustable to prevent ringing the bell when the body is in motion and the parts being readable for causing the bell to ring with movement of the body, simultaneously rotative members variably adjustable when rotated according to different determined adjustments for controlling the adjusting of the adjustable parts whereby the mechanism will ring the bell and subsequently prevent ringing the bell with the driving of the driven shaft by movement of the body, and spring actuating means operative for independently operating the mechanism with its separation from the driven shaft to cause sounding of the alarm.

32. The combination, in a safety device, with a bell, a shaft adapted to be driven by a movable body when in motion and mechanism detachably connected to and operative by the driving of the driven shaft for ringing the bell at intervals, of rotative members simultaneously adjustable according to different determined adjustments for controlling the operation of the mechanism whereby the bell will be selectively rung and prevented from ringing with the driving of the driven shaft by movement of the body, and spring actuating means op-

erative for independently operating the mechanism with its separation from the driven shaft to cause sounding of the alarm.

33. The combination, in a safety device, with a bell adapted to be mounted on a body and a shaft adapted to be driven by the body when in motion, of mechanism detachably connected to the driven shaft for being operated to ring the alarm, said mechanism adapted to be releasably locked against normally ringing the bell when the body is in motion and when unlocked the mechanism adapted to be operated for ringing the bell by the operation of the driven shaft with movement of the body, and spring actuating means operative for independently operating the mechanism with its separation from the driven shaft to cause the bell to ring.

34. The combination, in a safety device, with a casing adapted to be mounted on a vehicle, a bell in the casing and a shaft in the casing, adapted to be driven by a drive member of the vehicle, of lockable mechanism in the casing, operative by said driven shaft for ringing the bell, a shaft journaled in the casing rotative according to different determined adjustments, locking drums simultaneously rotative with the rotation of the shaft for selectively locking the mechanism against normally ringing the bell when the vehicle is driven and the drums also being rotative with the rotation of the shaft to selectively unlock the mechanism for operating to ring the bell by the operation of the driven shaft with movement of the vehicle, and permutation means on the adjustable shaft for controlling the selective adjustments of said shaft.

35. The combination, in a safety device, with a casing adapted to be mounted on a vehicle, a bell in the casing and a shaft in the casing, adapted to be driven by a drive member of the vehicle, of gearing in the casing, operative by the driven shaft, adjustable means in the casing, operative by the gearing for ringing the bell, a controlling shaft in the casing, adapted to be rotated according to different determined adjustments, and locking drums simultaneously rotative with the rotation of the controlling shaft for selectively adjusting the adjustable means to prevent ringing the bell when the vehicle is driven and the drums also being operative with the rotation of the controlling shaft to selectively readjust said adjustable means for ringing the bell with the operation of the gearing by the driven shaft operating with movement of the vehicle, and permutation means on the controlling shaft for controlling the selective adjustments of said shaft.

36. The combination, in a safety device, with a casing adapted to be mounted on a vehicle, a bell in the casing and a shaft in the

- casing, adapted to be driven by a drive member of the vehicle, of mechanism detachably connected to the driven shaft for being operated to ring the bell, said mechanism 5 adapted to be releasably locked against normally ringing the bell when the vehicle is driven, and when unlocked the mechanism adapted to be operated for ringing the bell by the operation of the driven shaft with 10 movement of the vehicle, a spring in the casing, adapted to be tensioned with the operation of said driven shaft whereby the bell ringing mechanism will operate with its separation from the driven shaft, and locking 15 means in the casing, operative with the tensioning of the spring to check the action of the spring when under a determined tension, said locking means also being operative with the separation of the bell ringing mechanism 20 from the driven shaft to release the tensioned spring whereby the bell ringing mechanism will operate independently of the operation of the driven shaft to sound the alarm.
- 25 37. The combination, in a safety device, with a casing adapted to be mounted on a vehicle, a bell in the casing and a shaft in the casing, adapted to be driven by a drive member of the vehicle, of mechanism in the casing, detachably connected to and operative by the driven shaft for being operated to ring the bell, controlling means operative according to different determined adjustments for releasably locking the mechanism 30 against normally ringing the bell when the vehicle is driven and the controlling means being operative to unlock the mechanism for ringing the bell by the operation of the driven shaft with movement of the vehicle, 35 a spring in the casing, adapted to be tensioned with the operation of said driven shaft whereby the mechanism will operate with its separation from the driven shaft, and locking means in the casing, operative 40 with the tensioning of the spring to check the action of the spring when under a determined tension, said locking means also being operative with the separation of the bell ringing mechanism from the driven 45 shaft to release the tensioned spring whereby the mechanism will operate independently of the operation of the driven shaft to ring the bell, and permutation means operative for controlling the selective adjustments of the controlling means.
- 50 38. The combination, in a safety device, a casing adapted to be mounted on a vehicle, a bell in the casing and a shaft in the casing, adapted to be driven by a drive member of the vehicle, of mechanism in the casing, detachably connected to and operative by the driven shaft, said mechanism having adjustable parts for ringing the bells, controlling 55 means operative according to a determined adjustment for adjusting the adjustable 60 parts of the mechanism into inaction to prevent ringing the bell when the vehicle is driven and the controlling means being operative to readjust said parts for operating to ring the bell by operation of the mechanism with movement of the vehicle, a spring in the casing, adapted to be tensioned with the operation of said driven shaft whereby the mechanism will operate with the separation from the driven shaft, and locking 65 means in the casing, operative with the tensioning of the spring to check the action of the spring when under a determined tension, said locking means also being operative with the separation of the mechanism from the driven shaft to release the tensioned spring whereby the bell ringing mechanism with its adjustable parts will operate independently of the operation of the driven shaft to ring the bell.
- 70 39. The combination, in a safety device with a casing adapted to be mounted on a vehicle, a bell in the casing, means in the casing, operative for ringing the bell, including a trip, a slidable shaft in the casing, having a locking bolt, a cam rotatable on the shaft and movable into and out of engagement with the trip of the bell ringing means with the slidable movement of the shaft when its bolt is locked and unlocked, controlling drums in the casing, rotatively adjustable according to determined adjustments for locking and unlocking the bolt to slidably adjust the shaft for moving the cam into and out of engagement with the trip of the bell ringing means, and gearing in the casing, operative by the vehicle when in motion for rotating the cam on the slidable shaft when adjusted by the unlocking of its bolt with the unlocking adjustments of the 75 controlling drums.
- 80 40. The combination, in a safety device, with a casing, a bell, means in the casing, operative for ringing the bell, including a trip, a slidable shaft in the casing having a locking bolt, a cam rotatable on the shaft and movable into and out of engagement with the trip of the bell ringing means with the slidable movement of the shaft when its bolt is locked and unlocked, controlling 85 drums in the casing, rotatively adjustable according to determined adjustments for locking and unlocking the bolt to slidably adjust the shaft for moving the cam into and out of engagement with the trip of the bell ringing means, a driven shaft journaled in and also slidable inwardly and outwardly of the casing, gearing operative by a drive member of the vehicle when in motion for driving the driven shaft, gearing in the casing, operative by the driving of the driven shaft for rotating the cam on the slidable shaft when adjusted by the unlocking of its bolt with the unlocking adjustment of the 90 controlling drums and said gearing being 95
- 100 105 110 115 120 125 130

detachable from the driven shaft, and spring actuating means, operative with the detaching of the gearing from the driven shaft for operating the gearing independently of movement of the vehicle.

41. The combination, in a safety device, with a casing adapted to be mounted on a vehicle, a bell in the casing, means in the casing, operative for ringing the bell, including a trip, a slidable shaft in the casing, having a locking bolt, a cam rotatable on the shaft and movable into and out of engagement with the trip of the bell ringing means with the slidable movement of the shaft when its bolt is locked and unlocked, controlling drums in the casing rotatively adjustable according to determined adjustments for locking and unlocking the bolt to slidably adjust the shaft for moving the cam into and out of engagement with the trip of the bell ringing means, a driven shaft journaled in and also slidably inwardly and outwardly of the casing, gearing operative by

a drive member of the vehicle when in motion for driving the driven shaft, gearing in the casing, operative by the driving of the driven shaft for rotating the cam on the slidable shaft when adjusted by the unlocking of its bolt with the unlocking adjustments of the controlling drums and said gearing being detachable from the driven shaft, means operative for locking the driven shaft to the casing when separated from the gearing, and spring actuating means operative with the detaching of the gearing from the driven shaft for operating the gearing independently of movement of the vehicle.

This specification signed and witnessed this 29 day of December A. D. 1922.
